UNITED STATES PATENT OFFICE

HORACE F. GRUMAN, OF RICHMOND HEIGHTS, MISSOURI, ASSIGNOR TO LEWIS INVISIBLE STITCH MACHINE COMPANY, OF KITTERY, MAINE, A CORPORATION OF MAINE

METHOD OF AND APPARATUS FOR OPERATING ON TUBULAR ARTICLES

Application filed March 30, 1925. Serial No. 19,382.

This invention relates to sewing machines and more particularly to means for performing certain kinds of special sewing operations. More specifically the present invention provides a method and apparatus for sewing a band into a hem or casing formed usually at the end of a tubular article of wearing apparel such as bloomer legs or the like.

10 In the operation of inserting a band such as an elastic band into the hem of a tubular article it is necessary to guide the band into the hem or casing as the latter is formed. When the operation is nearly completed and 15 the stitching mechanism has traversed nearly the complete circuit of the tubular article, guiding the band must be discontinued so that the casing may be completely closed by stitching.

20 One of the objects of this invention, therefore, is to provide a method whereby a casing may be formed on such a tubular article and the band guided thereinto during the forming operation but in which the guide is 25 removed just before completing the formation of the casing.

Another object is to provide improved apparatus for forming such a casing and for guiding the band into the casing as it is 30 formed.

Another object is to provide such an apparatus constructed that the guide may be removed from the casing prior to completing the formation of the same.

35 Further objects will appear from the following description taken in connection with the accompanying drawing in which:

Figure 1 shows an outline front view of a sewing machine provided with a band inserting mechanism embodying this invention;

Figure 2 is an end view of the same;

Figure 3 is an enlarged front view of the casing forming and band guiding mechanism, showing in section the material being operated upon;

Figure 4 is an enlarged perspective view of the casing forming mechanism and the band guide shown in operating position;

50 Figure 5 is a similar view but showing the

band guide moved so as to disengage the work;

Figure 6 is a view showing a section of the completed work; and

Figure 7 is a perspective view showing the 55 casing forming mechanism and band guide in operating position just prior to being removed for completing the formation of the casing.

Referring to the accompanying drawing 1 60 designates the body of the sewing machine of a suitable construction having a stitching mechanism including a needle bar 2 which in the present instance carries a pair of needles 3. The machine may be provided with a cylindrical support 4 over which the tubular article to be operated upon may be passed so that it may be engaged by the stitching mechanism. The support 4 may contain the shuttle and allied parts of any suitable type of 65 stitching mechanism adapted to co-operate with the needles 3, for stitching the work. A presser foot 5 of any suitable construction may be provided. All of these parts may be of any suitable construction well known in the 70 art and need not, therefore, be illustrated or described in further detail.

Mounted on the body 1 is a pair of supports 6 and 7 in which a horizontally movable rod 8 is slidably mounted. This rod has adjustably fixed thereon a pivot block 9 to which is pivoted a link 10 connected at its other end with one arm of a bell crank 11 pivoted at 12 on the body 1 and the other arm of which has connected thereto a chain 13 or other suitable 75 connection leading to a suitable manipulative element such as a foot pedal, not shown. A spring 14 connects the block 9 with the body 1 so as to maintain the rod 8 in retracted position as shown in Figure 1. This construction 80 provides that the operator, by pressing downwardly on the foot pedal so as to pull the chain 13, may move the rod 8 to the left, Figure 1. An adjustable collar 15 on the rod 8 85 may be set to limit such movement while an adjustable screw 16 on the body 1 provides an abutment or stop for limiting the movement of the rod 8 to the right, Figure 1.

The rod 8 has attached thereto by means of 90 off-set members 17 and 18 a parallel guide rod 100

19 arranged to slide in the support 7 and adapted to steady the rod 8 and prevent its twisting in its bearings. Attached at the end of the rod 8 is a downwardly extending post 20 which may be integral with the member 18. 5 Mounted at the lower end of the post 20 adjacent the support 4 is a guide block 21 having mounted thereon a curved guide-plate 22 adapted for cooperation with a similar but 10 oppositely faced guide-plate 23 adjustably mounted on the support 4. The plate 23 is provided with a slot 24 co-operating with a clamping screw 25 by means of which the guide 23 may be set in any adjusted position 15 upon the support 4. The mutually facing concave surfaces of the guides 22 and 23 serve to guide the material 26 so as to form a loop or casing as shown in Figure 3.

The block 21 also has mounted thereon a 20 forwardly extending arm 27 carrying a guide block 28. The block 28 is provided with a pair of inwardly extending horns 29 adapted to confine the edges of the band. Extending rearwardly from the horns 29 is a shallow 25 channel member 30 extending toward and partly into the space between the guides 22 and 23 as illustrated in Figure 4. This channel member 30 terminates in a beveled rear edge 31. Adjustably mounted on the guide 30 block 28 by means of a clamping screw 32 engaging the slot 33 therein is a gauge 34. This gauge is adjustable on the guide block by moving the same to the right, Figures 4 and 5, and serves to determine the extent or 35 width of the loop formed in the material in forming the casing, the guide 23 being adjusted accordingly.

The operation of this device is as follows:

The band which is to be inserted in the 40 tubular article, and which in some cases may be endless, is passed over the support 4 and laid into the guide block 28 and channel 30, its edges being inserted under the horns 29. The tubular article is then passed over the 45 support 4 and under the guide block 28 and inserted under the band. The end of the tubular article is then passed upwardly between the gauge 34 and the guide 23, back over the channel member 30 and the band 50 therein, downwardly between said member 30 and the guide 22 and back into the slot 35 formed in the guide block 28. The method of inserting the band 36 and the tubular member 26 is illustrated in Figure 3. The 55 material is thus formed at its end into a loop surrounding the band. This loop is then properly adjusted under the needles 3 and confined by the presser foot 5. The article is now in position for stitching the casing. If 60 the band 36 is an endless elastic one the operator stretches it so that the material 26 will lie flat without gathers. He then starts the sewing machine so as to stitch the casing. As this operation continues the operator allows the material to be fed through the ma-

chine by the feeding mechanism, keeping the elastic band stretched and the material flat. As the operation goes on the guides 23 and 22 fold the material over the band 36 which at the same time feeds through the guide formed by the block 28 and the channel 30. 75 This guide is so placed as to feed the band between the two lines of stitching. In cases where only one line of stitch is employed the band is fed between said line and the end of the casing. This operation produces a casing with the band included. As the tubular article moves around the support 4 during the stitching operation the point of commencement of the stitches approaches the stitching mechanism. When the operation is nearly completed the machine is stopped and the casing opened as illustrated in Figure 7. At the same time the band 36 is disengaged from one of the horns 29 as shown in this figure. The operator now presses down upon the foot pedal so as to rock the bell crank 11, thereby moving the rod 8 to the left and carrying the post 20 with the guide 22 and the guide block 28 to the left Figure 1. As will be seen from Figure 7 this movement is permitted as the casing is still open at that side. The post 20 and its attached guide members then take the position illustrated in Figure 5 at a distance from the stitching mechanism. The operator now closes the casing and while keeping his foot on the foot pedal starts the sewing machine and completes the formation of the casing. When this operation is completed the article may be disengaged from the guide 23 and removed by passing it under the block 28. A section of the completed article, in the case where an elastic band has been inserted, is illustrated in Figure 6.

105 It will be seen, therefore, that in accordance with this invention a method and apparatus are provided by which a band may be inserted in a suitable casing at the end of a tubular article. This operation is carried out in a simple and convenient manner. The band is guided into the casing during the formation of the same and between the lines of stitching. The arrangement is such that the guide may be quickly disengaged and moved out of the casing. It will be seen that this device enables the operator to perform such a banding operation in greatly reduced time so that the production of a stitching machine is correspondingly increased. It has been found in practice that an increase in production of 50% over previous methods is easily attainable. The adjustable gauge 34 provides for adjusting the extent of the casing beyond the outer line of stitching so that a ruffle or similar finish of any desired width may be formed at the end of the article.

110 It is obvious that various changes may be made in the details of construction without 115

departing from the spirit of this invention; it is to be understood, therefore, that this invention is not to be limited to the specific details shown and described.

5 Having thus described the invention what is claimed is:

In a machine of the character described, means for folding the material to form a casing, means for stitching the formed casing, a band guide, constructed and arranged 10 so that said guide may be positioned to guide a band into the casing or be moved clear of the casing, and means for adjusting the size of the casing.

15 In testimony whereof I affix my signature this 19th day of February, 1925.

HORACE F. GRUMAN.
